UNITED STATES PATENT OFFICE

EUGÈNE MATHIEU, OF NEUILLY-SUR-SEINE, FRANCE

CARBURETOR

Application filed April 9, 1930, Serial No. 442,786, and in France April 30, 1929.

The present invention relates to carburetors for internal combustion engines, and it has chiefly for its object to improve the atomizing of the liquid fuel by the air and 5 to obtain a substantially constant proportion of fuel in the mixture at the different rates of suction of the engine.

To this end, an important feature of the invention consists of an improved arrangement for the atomizing of the so-called primary mixture, wherein the liquid fuel under pressure is sprayed at a point below the constant level in the form of a spread-out sheet or radial jets, into an annular conduit in 10 which is circulated a thin cylindrical stream of primary air and which comprises a restricted part situated at the level at which the fuel is sprayed out, whereby the primary air will be given a great speed at this point, 15 20 the angle between the direction of the current of primary air of tubular form and said sheet or jets of liquid fuel being substantially 90 degrees.

Another important object of the invention 25 consists in the provision of a device for correcting the composition of the fuel mixture at high speeds of the engine, and for atomizing the fuel for the correction, or correcting fuel, the arrangement being such that the delivery of liquid through the correcting orifices will be impeded to a greater degree according as the speed of the primary air is greater.

Another feature of the invention consists 35 of a particular disposition of the parts of the nozzle, in order to assure a progressive suction as well as an atomizing of the reserve supply of liquid which collects in the recesses or chambers surrounding the nozzle during 40 stoppage or slow-running periods, and which forms the reserve of liquid by which the speeding up of the engine is facilitated.

Further features of the invention will be 45 specified in the following description, with reference to the accompanying drawings, which show, by way of example, various embodiments of the invention.

Fig. 1 is a partial vertical section of a carburetor of the vertical type.

Figs. 2 to 7 are partial sections of atomizers according to different modifications.

Fig. 8 is a sectional view of an atomizer showing a different arrangement.

Figs. 9 and 10 are diagrammatic sectional views showing modifications of the atomizer.

Figs. 11 and 12 show respectively in vertical section and in plan view a device for the discharge of the primary mixture into the engine suction conduit, in the case of a horizontal carburetor.

Figs. 13 and 14 are views similar to Figures 11 and 12, respectively, relating to a modification.

Fig. 15 shows an atomizer having several elements arranged in series.

Figs. 16 to 18 are sectional views of atomizers provided with correcting orifices.

Fig. 19 shows a device for atomizing the reserve supply of fuel.

Fig. 20 is a vertical section of a horizontal carburetor comprising a device for atomizing the reserve supply of fuel, and,

Figs. 21 and 22 relate to modified devices for atomizing the reserve supply.

The carburetor represented in Figure 1 comprises a float chamber 1, at the lower part whereof opens a duct 2 formed in a boss 3, which projects into the suction conduit 4 of the engine and supports the atomizing device denoted generally by 5, and in which is effected the mixture of the liquid fuel entering through duct 2 and the primary air entering through a conduit 6. The primary mixture proceeds from said atomizing device through a nozzle 7 into a Venturi tube 8, mounted in the suction conduit 4, beyond which is a throttle 9 or other throttling means.

The carburetor is further provided with a nozzle for slow-speed running, said device being connected by a channel 10 with the cylindrical chamber in which is mounted the atomizer; the slow-speed atomizer 12 is supplied with primary air by a conduit 13, connected by a duct 13* opening into the float chamber, having a communication with the atmosphere, as usual. The slow speed atomizer delivers the primary mixture into a channel 14, leading into the suction conduit 4 at

a point near the throttle when the latter is in the closed position.

An important feature of the invention consists in the improved construction of the atomizing device for the primary mixture. Said device comprises a member 20, whose end constitutes the nozzle 7 and which is formed with a venturi 21; the lower tubular end of said member is fitted upon a cylindrical boss of a nozzle 22, having an axial calibrated hole 23 which forms the main jet, and is extended by a conduit 24 of larger diameter, ending in a cup-shaped portion 25. Within conduit 24 extends a small tube 26, ending in a head 27 of ovoid or other shape, which cooperates with said cup-shaped portion to form an annular slot 28, situated at a determined level below the constant level of the fuel in the float chamber. At the lower part of member 20 are formed large apertures 29 for the entrance of primary air, and the cross sectional area between the inner wall of tube 20 and the periphery of the ovoid head 27 is accurately calibrated so as to form a restricted part 30.

As herein represented, the slow-speed atomizer may consist of a similar arrangement, comprising for instance a member 31, having an axial conduit 32, and screwing into a boss 33; its lower tubular part 34 is engaged upon an atomizer 35, having a spherical head 36 and pierced with an axial conduit 37 ending in a calibrated orifice 38, forming a slow-speed jet. A plurality of small inclined conduits 39 lead into the central conduit 37. Large apertures 40 for the entrance of primary air are formed at the bottom of the tubular part 34.

The operation is as follows:

When in the idle position, the liquid fuel, under head resulting from the difference of level, will flow through the calibrated orifice 23 and the annular slot 28, thus filling the chambers 41-42; it then proceeds through channel 10 and fills the slow-speed device 12; the main atomizing device and the slow-speed device are thus both submerged, and the liquid reaches the level T-T in all these parts.

When the engine is started and speeded up to normal speed, after having passed through the slow-speed period, as will be further specified, the suction of the engine cylinders draws primary air through the conduit 6, and the liquid fuel is drawn from the chambers 41-42 into the suction conduit 4 and thence into the engine cylinders.

When the reserve supply of fuel is exhausted, the primary air, which flows downwardly through conduit 6 rises in chamber 41 and, when passing through the restricted part 30, is imparted a great speed. The liquid fuel sprayed out through the annular slot 28, firstly by reason of the constant head due to the difference of level, and secondly in

virtue of the suction, will flow out in the form of a sheet which is spread in the restricted part 30 and meets the thin cylindrical stream of air which flows at high speed in this portion, at an angle of about 90°; this causes an abrupt impact between the fuel and the air, which assures an approved atomizing of the fuel and the homogeneity of the primary mixture. This latter is drawn into the admission conduit 4 of the engine, and mixes with the secondary air, then proceeding to the cylinders.

If the driver now closes the throttle 9, the suction ahead of the throttle is annulled, and the fuel which continues to be supplied under the effect of the static head, will again fill the chambers 41-42 and will flow through channel 10 to the slow-speed device. In the closed position of the throttle 9, a strong vacuum prevails in the region 43 in which the slow-speed channel 14 opens into the suction conduit 4, thus causing primary air to enter through conduit 13; this primary air, when rising between the head 36 of the slow-speed atomizer 12 and the tube 34, will acquire a great speed, thus effecting a most approved atomizing of the liquid fuel issuing through the small conduits 39.

In addition to this excellent atomizing of the fuel, this arrangement will also provide for a great increase of the amount of primary air at the expense of the secondary air, thus reducing the inertia or momentum of the mixture and facilitating the speeding up of the engine. This possibility is due to the fact that the restricted part or calibrated section 30 for the flow of primary air is situated just at the level at which the spray is delivered, thus permitting very large flow sections 29 for the air ahead of the restricted conduit 30. This result cannot be obtained in the known carburetors, in which the orifices for the entrance of primary air are located beyond the nozzle, and hence cannot be much enlarged, as this would unduly reduce the vacuum on the nozzle.

Obviously, this construction is given solely by way of example; it is applicable to carburetors of the horizontal type (Fig. 20) as well as to carburetors of the vertical type. The invention is independent of the construction of the slow-speed nozzle, which may be of any known type.

The head 27 of the atomizer, instead of having an ovoid shape, may be given a spherical, tapered, cylindrical or stepped shape, or any other suitable form, adapted to provide a restricted flow section for the primary air at the spraying level. By way of example, Figures 2 and 4 show an atomizer with tapered head, and Figures 3, 5, 6 and 7 relate to atomizers with round heads (like the head 36 of the slow-speed atomizer of Fig. 1), as well as various dispositions of slots or apertures for spraying the fuel.

Instead of spraying the fuel in the form of a spread-out sheet, through an annular slot, this may be delivered, as above indicated for the slow-speed nozzle of Figure 1, through 5 radial ducts, in such manner as to produce a certain number of radial jets, or the annular slot may be combined with radial ducts. Thus, in Figure 4, the liquid fuel enters the annular slot 28 through inclined ducts 45; the 10 same is shown in Figure 5, which relates to a modification. In Figures 6 and 7, the channels 46 for the discharge of the fuel are pierced horizontally in the plane of the annular slot 28. Obviously, many other modifications may be provided for spraying the liquid in a spread-out sheet, or in radial jets having an angle of about 90° with reference to the direction of the current of primary air.

In like manner, the mounting of the 20 atomizer may be different; thus, as shown in Figure 8, member 7, instead of being screwed into the boss 3, has a shoulder 48 in contact with the flanged edge 49 of a sleeve 50, whose threaded lower part is screwed upon a member 51, screwed into the boss 3, and having large apertures 52 for the entrance of primary air. Extending from member 51 is a tube 53, which forms a baffle for the primary air between the orifices 52 and 29.

30 Instead of spraying the fuel from the center to the periphery, it may be sprayed from the periphery towards the center, as shown in Figure 9; herein the fuel supplying conduit 2 has a calibrated orifice or jet 55 and 35 opens into an annular chamber 56, surrounding a primary air conduit 57 and in communication therewith through orifices 59. Within conduit 57 is a concentric core 58, which may have the shape of two cores with 40 a common base, thus leaving an annular passage whose cross-section decreases up to the spraying point, at which the primary air assumes its maximum speed. The fuel may also be sprayed through a slot at the level 45 of the restricted part 59.

Fig. 10 shows an arrangement in which the liquid is sprayed from the periphery towards the center by means of the last mentioned device on the one hand, and from the 50 center to the periphery by radial ducts 60 pierced in the central core 58 and communicating with a second liquid supplying conduit 61, on the other hand.

The perfectly homogeneous primary mixture, in which the liquid is finely atomized by 55 means of the aforesaid devices is preferably delivered into the engine suction conduit by means providing for the spreading of the current of primary mixture, this furthering its 60 diffusion into the secondary air. This result is obtained in Figure 1 by the diverging cone of the venturi 21. In horizontal carburetors, it is possible to use the device shown in Figs. 11, 12 and 20, in which the 65 primary mixture issues through a round

head 65, slotted at 66 in a direction perpendicular to the direction of flow f of the secondary air. The primary mixture issues radially in a fan-shaped sheet, and is subjected to the abrupt impact of the current of secondary air, and thus a homogeneous mixture is more readily obtained. Figs. 13 and 14 show a similar disposition, but herein the head 67 is reduced to a hemisphere, with the convex side turned towards the intake of the 70 suction conduit.

Figure 15 shows a device for the exit of the primary mixture in the case of a vertical carburetor, wherein the structure of the head 68 is similar with that of the head of the atomizer used for the primary mixture. This figure also shows, by way of example, several atomizers arranged in series 69, 70, 68; the primary air enters through conduit 6 and apertures 29, and is divided into two currents, one of which flows at high speed at the level of the slot 73 of atomizer 69 and the resulting mixture issues through the slot 71 of the second atomizer 70, before which the second current of primary air flows at high 80 speed, and the final mixture is discharged through the slot 72 of the head 68 into the intake conduit 4 of the engine.

In the carburetor above described, the excessive enriching of the fuel mixture occurring at high speeds of the engine is partially corrected due to the fact that the fuel is sprayed under a constant head h (Fig. 1), which constitutes the factor of correction. However in certain cases, and chiefly in order 90 to reduce the amount of fuel stored during stoppage in the recesses 41-42 of the sprayer, it may be necessary to reduce the difference of level h and hence to reduce the relative value of the correcting factor constituted by this level difference.

To obviate this defect, and according to another feature of the invention, to the main sprayer 23 (Figures 16, 17 and 18) may be added one or more correcting orifices 80 communicating with the fuel supply conduit 2 or 81 ahead of the main jet 23 and opening at a point near the apertures 29 for the abundant supply of primary air. Primary air (Fig. 16) entering through said apertures 29 will impinge upon the part 82 of the atomizer, thus producing whirls and eddies and reducing the suction or vacuum, and especially as its speed is greater, so that the delivery of orifice 80 will be checked according as the speed of the primary air is higher, that is, as the vacuum in the engine intake conduit is greater. At the same time, the primary air effects the atomizing of the correcting fuel discharged from said orifices 80. The correcting orifice is supplied under a constant head, thus affording another factor for correcting the composition of the mixture.

As shown in Figure 17, the correcting orifices 80 may be arranged on the axis of the 130

air inlets 29, thus increasing the impeding action of the primary air. The calibrated orifice 23 or main jet is still ahead of the correcting orifices 80, as shown.

5 In Figure 18, the correcting orifices 80 are inclined in such manner that the fuel will be sprayed in the contrary direction to the current of primary air, and herein the checking action is very energetic, and may be even 10 strong enough to entirely stop the delivery of the correcting orifices 80.

Said correcting orifices 80 have another advantage, that is to render more efficient the atomization of the sprayed out fuel. The 15 primary air which flows in the conduit 41 is loaded with some emulsified fuel when passing before said correcting orifices. Its density is thus increased, so that the impact of said air against the fuel sprayed out beyond 20 orifices 80 is also increased and, consequently, the atomization of the fuel spray is better.

A serious disadvantage in the known carburetors resides in that the primary air abruptly withdraws the supply of liquid fuel 25 stored in the several recesses, when the engine starts running or is speeded up, since the fuel thus taken up in excessive quantity is not properly atomized and is distributed irregularly among the engine cylinders; the excess 30 fuel removes the lubricating oil from the movable parts and mingles with the oil in the crankcase, thus causing gripping and wear and carbon deposits due to an excess of fuel in the mixture.

35 To obviate such defects, the reserve supply of fuel (Figs. 19-21) is contained in recesses or chambers which are protected against direct suction by the primary air, at least as concerns the major part of the volume of fuel, for causing a progressive withdrawal of 40 the reserve fuel, and means are provided for properly atomizing this reserve fuel by the primary air.

The simplest device for this purpose is 45 shown in Figure 19. A partition 90 separates chamber 41 from the space 91 serving for the normal flow of primary air entering through the apertures 92, and the lower part of said chamber 41, which communicates with 50 the annular space 42 by the openings 93-94, is connected by one or more ducts 95 with the conduit 24, situated beyond the sprayer 23. This arrangement has the following advantage. When the engine is started or speeded 55 up, primary air first flows through the apertures 92, thus expelling the small amount of fuel stored above partition 90; then the primary air forces the fuel contained in the annular space 42, as well as the fuel contained 60 in space 41, (by means of the orifices 93-94), through the duct 95 into the conduit 24; this fuel thus issues through the slot 28, or the radial ducts of the atomizer, and is subjected 65 to the action of the current of primary air entering through the apertures 92, as in the

case of Figure 1. Hence, the stored fuel is taken up in a very progressive manner, and it is efficiently atomized. When the fuel reserve is exhausted, a certain amount of primary air may enter through the duct 95, thus 70 already forming a certain emulsion in the conduit 24.

Figure 20, which shows by way of example a horizontal carburetor, shows a device quite similar to the preceding; the fuel flows 75 through conduit 2, main jet 23, duct 24 and is sprayed into conduit 91 through slot 28, where it meets the ascending current of air entering at 6 and flowing through orifices 92, the primary mixture being discharged 80 through the Venturi nozzle 7 and head 65 into the engine intake conduit 4. In normal operation, primary air also enters duct 24 through an opening 93 into which opens a correcting orifice 80 connected with the 85 fuel supply ahead of jet 23; the flow through this orifice is checked by the current of primary air flowing through opening 93, which may be followed, for this purpose, by a tapered conduit 96. In normal operation, the 90 primary air entering through duct 93 atomizes the correcting fuel issuing from the orifice 80, and reduces the delivery therethrough as the engine speed increases; the atomization of the fuel from orifice 80 is achieved 95 by reason of its flow through the atomizer 28. Orifice 93 also serves, when starting, to cause the reserve supply of fuel stored up in cavity 41, to enter duct 24 and to be atomized through the atomizer. 100

In Figure 21, the correcting fuel, instead of being led to the atomizer through the conduit 81 of the main jet 23, flows through a parallel conduit 98, opening into the slot 28 of the atomizer having a calibrated orifice or jet 99. This figure shows another disposition of the correcting orifice 80. 105

In Figure 22, only the conduit 24 of the main jet 23 opens into the annular slot 28 of the atomizer, whilst the separate conduit 98 for the reserve fuel opens through a calibrated orifice or jet 99 at the top of the atomizer head 27. 110

In certain embodiments of the invention, and more specifically when the fuel is supplied by two different paths (as in Figures 10, 11, 12, 13, 14, 15, 16, 17, 18, 19, 20, 21, 22) use may be made of two different fuels, namely a light fuel to further the speeding up and a heavy fuel for the power jet; thus, at slow speed running, the mixture will contain a greater proportion of light hydrocarbons, whilst the proportion of these latter will decrease as the speed rises, and this furthers the ignition by changing the igniting point in a suitable manner. This 115 cannot be done when the light and heavy fuels are preliminarily mixed together, since 120 said fuels generally lack miscibility. 125

This fuel supply method may be used, in 130 the case of Figure 10, by feeding heavy fuel

for instance, through the ducts 60 of the central core 58, and light fuel through the orifices 59 of the annular chamber 56, or conversely. The arrangement should be such 5 that the storage chamber 101 will be filled at rest with light fuel, which can be supplied for instance by a second float chamber, in which the constant level for the light fuel is properly selected according to the relative densities of the two fuels.

In Figures 16, 17, 18, 20, 21 and 22, the correcting orifices 80 can be used to supply the light fuel, by connecting said orifices with suitable feeding conduits in communication with a second float chamber. The two fuels can be atomized after they have been mixed together, as in the case of the carburetor shown in Figure 20, or they may be separately atomized, as in the case of Figure 22.

Obviously, the invention is not limited to the details of construction herein specified, and the carburetors above described are susceptible of numerous modifications without 25 departing from the scope of the invention.

Having now described my invention what I claim as new and desire to secure by Letters Patent is:

1. In a carburetor, a constant level fuel tank, an intake pipe adapted to be connected with an engine and an atomizer for the primary fuel mixture, said atomizer embodying means, below said constant level, for spraying fuel from said tank in a spread out spray, an annular conduit surrounding said spraying means, opening into said intake pipe and having a restricted cross section at the spraying level, and air inlet means opening into said conduit for supplying primary air thereto, the arrangement being such that the air flow assumes an increased speed and a smaller thickness through said restricted part and meets the fuel spray at an angle substantially equal to 90°.

45 2. In a carburetor, a constant level fuel tank, an intake pipe adapted to be connected with an engine, and an atomizer for the primary fuel mixture, said atomizer embodying a conduit having an air inlet and opening 50 into said intake pipe, a central member in said conduit and leaving a restricted passage between it and said conduit below said constant level, a spray outlet in said passage and means for connecting said tank with said outlet, whereby fuel is sprayed into said passage in a spread out sheet and meets at a substantially right angle a thin flow of primary air entering through said inlet and having an increased speed through said passage.

60 3. A carburetor as claimed in claim 1 wherein said spraying means consists of several radial circular holes opening into a continuous circular slot located in a plane substantially at right angles with said conduit.

65 4. In a carburetor as claimed in claim 1, a

primary mixture discharge nozzle at the end of said conduit and within said intake pipe, said nozzle having a convex surface facing the inlet of said intake pipe.

5. In a carburetor as claimed in claim 1, a second atomizer surrounding said first mentioned atomizer and embodying means, below said constant level, for spraying the primary mixture from said conduit in a spread out spray, an annular conduit surrounding said latter spraying means and having a restricted cross-section at the spraying level, and air inlet means opening into said latter conduit for supplying air thereto.

6. In a carburetor, a constant level fuel tank, an atomizer for the primary fuel mixture and a fuel supply channel between said tank and said atomizer, and having a calibrated orifice therein, said atomizer embodying means, below said constant level, for spraying fuel from said tank in a spread out spray, an annular conduit surrounding said spraying means and having a restricted cross section at the spraying level, air inlet means opening into said conduit for supplying primary air thereto, and a correcting orifice opening into said channel, ahead of said calibrated orifice, and into said conduit, adjacent said air inlet means, whereby the delivery of said orifice is counteracted by the flow of 95 entering air.

7. A carburetor as claimed in claim 6, wherein said correcting orifice opens into said conduit substantially in the axis of said air inlet means.

8. A carburetor as claimed in claim 6, wherein said correcting orifice is inclined towards said air inlet means in a direction contrary to the air flow.

9. In a carburetor, a constant level fuel tank, an atomizer for the primary fuel mixture and a fuel supply channel between said tank and said atomizer, and having a calibrated orifice therein, said atomizer embodying means, below said constant level, for spraying fuel from said tank in a spread out spray, an annular conduit surrounding said spraying means and having a restricted cross section at the spraying level, air inlet means opening into said conduit for supplying primary air thereto, and a duct for connecting said conduit ahead of said spraying means with said supply channel beyond said calibrated orifice, whereby any fuel contained in said conduit is forced through said duct, said channel and said spraying means.

10. In a carburetor as claimed in claim 9, a correcting orifice opening into said duct and into said supply channel ahead of said calibrated orifice and adapted to deliver fuel into the air current passing through said duct into said channel.

11. In a carburetor, a constant level fuel tank, and an atomizer for the primary fuel mixture, embodying means, below said con-

stant level, for spraying fuel from said tank in a spread out spray, an annular conduit surrounding said spraying means and having a restricted cross section at the spraying level, 5 air inlet means opening into said conduit for supplying primary air thereto, a correcting orifice opening into said conduit toward said air inlet means, and a further fuel supply connected with said correcting orifice.

10 12. A carburetor as claimed in claim 2, wherein said central member has an ovoid shape, the radial size of said member being smaller beyond said spray outlet than ahead of the latter.

15 In testimony whereof I have signed my name to this specification.
